C. DRAKE

DERRICK BRACE

Filed May 4, 1925

Inventor
CHARLES DRAKE

Ch. Drake

Attorney

UNITED STATES PATENT OFFICE.

CHARLES DRAKE, OF MANNINGTON, WEST VIRGINIA.

DERRICK BRACE.

Application filed May 4, 1925. Serial No. 27,973.

To all whom it may concern:

Be it known that I, CHARLES DRAKE, a citizen of the United States, residing at Mannington, in the county of Marion and 5 State of West Virginia, have invented certain new and useful Improvements in Derrick Braces, of which the following is a specification.

This invention relates to derrick braces, 10 and more particularly to braces adapted to be applied to the legs of a derrick.

An object of the invention is the provision of bracing means that will resist torsional strains on the legs of the derrick.

15 A further object is the provision of a brace of extreme simplicity that may be readily applied to derrick legs of different types.

In the accompanying drawings, I have shown one embodiment of the invention. In 20 this showing:

Figure 1 is a front elevation of the lower portion of a derrick showing the invention applied,

25 Figure 2 is a horizontal sectional view on line 2—2 of Figure 1, and,

Figure 3 is a perspective view of the ends of a pair of cooperating bracing members.

Referring to the drawings, the reference 30 numeral 1 designates the legs of a derrick. For the purpose of illustration, I have shown a derrick formed of tubular members, but the invention is susceptible of use with derricks of any character and in which the legs are formed of any desired cross 35 section. Similarly, the bracing members may be applied to a derrick having any number of legs and the number of braces employed corresponds to the number of legs of the derrick or tower.

40 Arranged horizontally and extending from one derrick leg to the next, I provide a bracing member 2, having each end of proper size and shape to extend substantially half way around the leg of the derrick.

45 When the derrick is circular in cross section, each end of the brace is provided with a substantially semi-circular portion 3 and beyond the semi-circular portion, I provide an extension 4. The extensions 4 are provided with suitable openings 5 for the 50 reception of bolts 6. At the inner end of the semi-circular portion, the brace is flattened,

as at 7, and is provided with an opening 8 for the reception of a bolt 9.

The operation of the device will be apparent from the foregoing description. The 55 bracing members 2 are placed in position so that the ends of two adjacent members will nearly surround the leg or post and cross each other at the inner ends of the portion 3 60 arranged around the derrick leg. The bolts 9 are then inserted in the openings 8 to connect the bracing members to each other and the bolts 6 are then inserted in the openings 5 and tightened. The ends of the two members 65 then serve as a clamp and when each end of each member is so fitted and clamped to each leg, the brace resists torsional strain on the leg or post and serves to hold the legs or posts in their original position with respect to each other.

70 It is to be understood that the form of my invention herewith shown and described is to be taken as a preferred example of the same, and that various changes in the shape, size, and arrangement of parts may be resorted to without departing from the spirit of the invention or the scope of the subjoined claims.

75 I claim:

80 1. In a device of the character described, a horizontally-disposed member adapted to extend from one derrick leg to the adjacent one, said members being provided with portions adapted to partially surround the derrick legs, said members being provided with flattened portions inwardly of said surrounding portions and being further provided with openings in said flattened portions whereby two adjacent members may be 85 secured to each other, and extensions arranged outwardly of said surrounding portions, said extensions being provided with openings for the reception of bolts whereby said surrounding portions may be clamped 90 around the derrick leg.

95 2. In a device of the character described, a plurality of horizontally disposed members each adapted to extend from one derrick leg to another, each end of each of said members being provided with an integral 100 arcuate portion adapted to partially surround one of the legs, and means for securing the arcuate portions to each other in-

wardly and outwardly of said arcuate portions.

3. In a device of the character described, a plurality of horizontally disposed members, each adapted to extend from one derrick leg to another, said members being provided with integral arcuate extensions adapted to partially surround the derrick leg, said members being provided with flattened portions inwardly of said surrounding portions, said flattened portions being provided with openings, a bolt passing through said openings, and means for securing the adjacent members to each other outwardly of said extensions.

4. In a device of the character described, a pair of horizontally disposed members arranged at an angle to each other and crossing at points spaced from one end thereof, said horizontal members being provided outwardly of their crossing points with integral complementary arcuate portions adapted to form a clamp to receive a derrick leg, and means for securing said members at their crossing point and outwardly of the arcuate portions.

20
25
In testimony whereof, I affix my signature.

CHARLES DRAKE.
